SURFACING MACHINE

Joseph J. Overzat, New York, N. Y.

Application March 10, 1945, Serial No. 582,095

7 Claims. (Cl. 51—26)

(Granted under the act of March 3, 1883, as
amended April 30, 1928; 370 O. G. 757)

1

This invention relates in general to surfacing machines and in particular to an improved multiple lapping machine. The process performed by the machine is disclosed and claimed in application Serial Number 711,333 filed November 21, 1946, by Joseph Overzat.

It is an object of this invention to provide a machine for surfacing workpieces, as by lapping, wherein the workpieces are subjected to a spiral abrading motion.

It is another object to provide a machine for surfacing workpieces, as by lapping, wherein the workpieces are subjected to a substantially spiral abrading motion.

It is a further object to provide a surfacing machine wherein the radius of the abrading motion is varied automatically in timed relationship with the abrading motion.

It is a further object to provide a machine for simultaneously surfacing a plurality of pairs of workpieces with oppositely configured mating surfaces.

Further objects and advantages of the invention will be apparent from the following detailed description in connection with the accompanying drawings, in which:

Fig. 1 is a perspective view of one embodiment of this invention.

Fig. 2 is a schematic top view showing the power transmission to the individual surfacing units.

Fig. 3 is a schematic side view, partially in section, showing the working parts of one of the multiple surfacing units.

Fig. 1 shows a preferred form of the machine having four separate lapping units generally designated 10, each mounted upon a supporting frame 11 the upper portion of which also carries a common power element such as a motor 12.

Each unit 10 (Figs. 1 and 3) has a base disc 13 adjustably mounted on the supporting frame 11 and adapted to apply upward pressure by means of a hand screw 14 and an inner spring 15. Adjacent to base disc 13 and substantially parallel to the surface thereof is located a lapping disc 16. The base disc 13 and lapping disc 16 are provided with clamps or fasteners 17 to support and retain workpieces 17a on which the lapping operation is to be performed.

Pivottally connected by a ball-and-socket joint 18 to lapping disc 16 is a spindle 19 provided with a universal joint 20 near the end remote from said disc 16. The lapping disc 16 is optionally guided by a movable rod 21, which is retained in its relative positional angle by means of sup-

2

port 22 on frame 11. The rod 21 prevents the lapping disc 16 from rotating while permitting it to move in a spiral path. The upper end 23 of the spindle 19 is pivotally connected to a rotary driving disc 24, rotatably supported by the supporting frame 11.

The driving disc 24 is provided with a friction clutch 25 comprising a male member 26 and female member 26a and adapted to be released or engaged by means of hand wheel 27 operating on screw threads (not shown). Connected to the male member 26 of clutch 25 is a bevel gear 29 arranged to transmit power to each unit 10. Meshing with the bevel gear 29 and transmitting power thereto is a bevel gear 30 mounted on a shaft 31 journaled in bearing brackets 31a. One of the shafts 31 carries a worm gear 32 driven by a worm 33 mounted on the motor shaft 34 of the motor 12.

Between the ends of spindle 19 there is a floating pivot or fulcrum 35 slidably connected to said spindle 19 by means of a ball-and-socket 36 having a bore 37 for slidably receiving the spindle 19. Fulcrum 35 is adapted to be moved reciprocably in a vertical direction by means of a rod 38, which operably interconnects each pair of fulcra 35. The rod 38 carries a pin 39 upon which links 40 are mounted. At their opposite ends the links 40 are connected to a pin 41 mounted upon a driving disc 42. The driving discs 42 are mounted upon a shaft 43 rotatably supported in bearing brackets 44 extending downwardly from the supporting frame 11.

To prevent motion other than vertical in said floating fulcrum 35, the rods 38 are provided with sleeve bearings 45 slidably mounted on guide rods 46. The guide rods 46 are secured at their upper ends to the upper portion of the supporting frame 11 and at their lower ends to a rectangular frame 47, which in turn is mounted upon posts 48 extending upwardly from the lower portion of the supporting frame 11. Mounted upon the shaft 43 is a worm wheel 49 (Fig. 2) within a reduction gear box 50. Meshing with the worm wheel 49 is a worm 51 mounted upon the cross-shaft 52 journaled in bearing brackets 53. The cross-shaft 52 at its opposite ends carries bevel gears 54 meshing with bevel gears 55 mounted on and driven by the shafts 31. One of the shafts 31, as previously described, is driven from the motor shaft 34 by way of the worm 33 and worm wheel 32.

In the operation of this machine, in any unit 10 the workpiece 17a on which the lapping operation is to be performed, is firmly fastened to the

discs 13 and 16 by means of the clamps 17, and a suitable abrasive applied. Pressure is applied by means of hand screw 14 and spring 15, the power is turned on, and the clutch 25 engaged. The driving disc 24 rotates causing the upper end 23 of spindle 19 to move in a circular path, thereby causing the spindle portions on opposite sides of the floating fulcrum 35 to describe conical paths around the floating fulcrum 35 acting as a pivot.

Simultaneously with the motion just described, the floating fulcrum 35 is caused to undergo reciprocal vertical motion, the gear ratio being such that this motion is relatively considerably slower than the motion of disc 16. The spindle 19 consists of two sections, one above the floating fulcrum 35 and one below the said fulcrum. As the floating fulcrum 35 reaches the bottom of its path, the lower section of said spindle 19 is proportionately much shorter than the upper section and, therefore, motion imparted to the lapping disc 16 is along a path of much smaller diameter than the path of motion of spindle end 23. As the fulcrum 35 reaches the top of its path, the lower section of spindle 19 is proportionately longer than the upper section and, therefore, the motion imparted to disc 16 is along a path of comparatively larger diameter than the path of motion of spindle end 23. In this manner the lapping disc 16 undergoes motion along a spiral path thus making it ideally adapted to lapping operations by evenly distributing the abrasive and by continually varying the path of the abrading motion and breaking up any repetitive regular motion.

By means of clutches 25 each of the units 10 can be independently disconnected from the power source 12. Accordingly it is possible for each unit 10 to operate independently of the others. In this way one operator can maintain all of units 10 in substantially constant operation without necessitating the shutting down of the entire machine for the removal of one piece of work.

This apparatus can be adapted to numerous similar uses. For example plane surfaces can be buffed or lapped with this apparatus. Larger or smaller articles can be lapped by suitable adjustment of the lower lapping disc 13. In cases where it is desired to lap extremely large objects, the base disc can be completely removed and the article to be lapped supported and held in contact with the lapping surface by other appropriate means. The lapping disc 16 by virtue of its pivotal connection to the spindle 19 automatically adjusts itself to curved, regular surfaces of substantially all sizes, thereby eliminating the necessity for frequent adjustments between operations.

In the process of this invention one of the workpieces 17a is moved in a spiral path while the surfacing operation is being performed. While the invention is described in connection with lapping two workpieces 17a with mating surfaces, one of the workpieces 17a can be replaced by a lap or tool having a plane or spherical surface whose configuration is transferred to the workpiece 17a by the operation of the machine.

It is to be understood that various modifications and changes may be made in this invention without departing from the spirit and scope thereof as set forth in the appended claims.

The invention described herein may be manufactured and used by or for the Government of the United States of America for governmental

purposes without the payment of any royalties thereon or therefor.

What is claimed is:

1. A machine for surfacing a workpiece comprising a supporting member for the workpiece, a surfacing member associated therewith for providing a configuration to be imparted to the workpiece, a rotary driving element, a driven element operatively connected at one end to said driving element and at the other end to one of said members respectively, a fulcrum engaging said driven element at a location intermediate its ends, a power means for rotating said driving element, and mechanism operatively connected to said power means for moving said fulcrum relative to the ends of said driven element whereby to cause the portions of said driven element on opposite sides of said pivot to describe conical paths of varying radii.

2. A machine for surfacing a workpiece comprising a support member for the workpiece, a surfacing member, a rotary driving element, a driven element operatively connected adjacent its opposite ends to said driving element and to one of said members respectively, a fulcrum engaging said driven element at a location intermediate its ends; a power means for rotating said driving element, and mechanism operatively connected to said power means for moving said fulcrum relative to the ends of said driven element whereby to cause a movable contact between said members, said contact moving in a path whose projection upon a plane perpendicular to the axis of the workpiece member is a spiral.

3. A machine for surfacing a workpiece comprising a support member for the workpiece, a surfacing member, a rotary driving element, a driven element operatively connected adjacent its opposite ends to said driving element and to one of said members respectively, a fulcrum engaging said driven element at a location intermediate its ends, a power means for rotating said driving element, and mechanism operatively connected to said power means for moving said fulcrum relative to the ends of said driven element whereby to cause a movable contact between said members, said contact moving in a substantially spiral path.

4. A machine for surfacing a workpiece comprising a support member for the workpiece, a surfacing member, a rotary driving element, a driven element connected adjacent its opposite ends eccentrically to said driving element and to one of said members respectively, a fulcrum engaging said driven element intermediate its ends, and means for moving said fulcrum along a path between said driving element and the connected member.

5. A machine for surfacing a workpiece comprising a support member for the workpiece, a surfacing member, a rotary driving element, a driven element connected adjacent its opposite ends eccentrically to said driving element and to one of said members respectively, a fulcrum engaging said driven element intermediate its ends, means for rotating said rotary driving element, and means for synchronously moving said fulcrum along a path between said driving element and the connected member.

6. A machine for surfacing a workpiece comprising a support member for the workpiece, a surfacing member, a rotary disc, a spindle adjacent one end connected eccentrically to said disc and adjacent the other end connected to one of said members, a ball-and-socket fulcrum engag-

ing said spindle intermediate its ends, means for rotating said rotary disc, and means connected with said first means for moving said fulcrum synchronously with rotation of said disc along a path between said disc and the connected member.

7. A machine for surfacing a workpiece comprising a support member for the workpiece, a surfacing member, a fulcrum, a lever engaged by said fulcrum, said lever adjacent one end being connected to one of said members, means for moving said lever adjacent its other end in a circular path, and means for synchronously moving said fulcrum along a path between said means and the connected member.
